DOOR PULL FOR A SLIDING DOOR

Salvatore Merendino, Pasadena, Calif., assignor to Arcadia Metal Products, Fullerton, Calif., a corporation of California

Application February 20, 1956, Serial No. 40,225

Term of patent 14 years

(Cl. D10—8)

Fig. 1.

Fig. 2.

Fig. 3.

Fig. 4.

Fig. 1 is a perspective view of a door pull for a sliding door embodying my new design.

Fig. 2 is a front view of the door pull shown in Fig. 1.

Fig. 3 is a side view taken from the left of Fig. 2.

Fig. 4 is a bottom end view of Fig. 2.

I claim:

The ornamental design for a door pull for a sliding door, substantially as shown.
